FASTENING DEVICE

James F. Cleary, Kansas City, Mo.

Application September 18, 1939, Serial No. 295,369

2 Claims. (Cl. 229—47)

This invention relates to fastening devices, and more particularly to fasteners for securing closures to containers, such as corrugated and/or solid fibre or other composition shipping boxes for fruits, eggs, vegetables and the like, the principal object of the invention being to provide an easily operated, economical and efficient fastening device for such purpose.

In shipping fruit, for example, it is desirable to hold the fruit in the position in which it was packed in order to prevent bruising and other damage to the fruit normally produced by impacts of the articles against each other as an incident to bouncing and rocking, while in transit, of the vehicle in which the packed fruit is shipped. It is also desirable to allow for inspection of the commodities during shipment and to avoid as far as possible, the danger of injury to handlers of the containers, as by cutting or scratching themselves on the fastening devices.

Further objects of the present invention are, therefore, to arrange the fastening devices in accordance with this invention in such a manner as to cooperate with the containers and closures therefor in holding the commodities packed in the containers in desired position; to so arrange the fastening devices as to allow for opening the containers and reusing the fastening devices on the same or other containers; to reduce open projecting edges of the fastening devices to a minimum; to provide an effective lock for the fastening devices as an incident to their application to the containers and closures with which they are associated; and to provide improved elements and arrangements of elements in fastening devices of this character.

In accomplishing these and other objects of the present invention, I have provided improved details of structure, the preferred forms of which are illustrated in the accompanying drawing, wherein:

Fig. 1 is a fragmentary perspective view of a container and closure having a fastening device embodying the features of the present invention applied thereto.

Fig. 2 is a detail perspective view of a locking member constructed in accordance with the present invention.

Fig. 3 is a detail vertical transverse section through the container and closure on the line 3—3, Fig. 1.

Fig. 4 is a detail perspective view of a terminal for the fastening device, the same being shown in semi-engaged relation to the container and locking member.

Fig. 5 is a perspective view similar to Fig. 4 with the fastening device terminal in engaged relation to the container and locking member.

Fig. 6 is a detail perspective view of a terminal of the fastening device, a modified form of locking member being illustrated.

Fig. 7 is a view similar to Fig. 6 showing a terminal of the fastening device in semi-engaged relation to a container and modified form of locking member.

Fig. 8 is a detail vertical cross-section through a container and closure therefor showing a terminal of the fastening device in positive locking relation to the container and locking member.

Referring more in detail to the drawing:

1. Fig. 1, designates a container which is preferably formed of fibre or like board and provided with downturned reinforcing flanges 2 and 3, Fig. 3, on the upper edges of the side walls 4 and 5 of the container. The end walls of the container are preferably provided with upstanding edges 6 and 7 relative to the upper edges of the side walls for supporting opposite ends of a closure 8 for the container. The ends 9 of the container closure are suitably arranged for anchoring engagement of the closure with the container and where, as here, the closure comprises overlapping portions, fastening devices 10 and 11 are preferably provided to hold the closure portions in suitably overlapped container closing position.

In a container and closure therefor constructed as described, it has been found desirable to brace and further fasten the closure to the container, particularly for the purpose of holding the closure throughout its area in contact with commodities, such as fruit, packed in the container, to thus prevent relative movement of the fruit in the container while being shipped, and thus avoid bruising or otherwise damaging the fruit by impact of the individual articles with each other.

In accordance with the present invention, therefore, anchors 12 and 13, which are preferably in the form of raised type staples, are mounted on the container on substantially oppositely disposed portions thereof, preferably adjacent the lower edges of the downturned side wall flanges 2 and 3 approximately mid-way the length thereof, as clearly shown in Fig. 1.

An elongated bendable element 14, such as a strip of bendable metal tape or the like is next provided, the tape having a terminal 15 adapted for extension upwardly, as shown in Fig. 3, between a side wall of the container and the anchor 13. The tape is then bent upwardly on the fold line 16 and preferably transversely in su-

per-imposed relation to the closure. Each bend of the tape aids in locking the fastening device in desired position and cooperates with the anchors in fastening the closure to the container. The tape is further bent downwardly on the fold line 17 at the edge of the closure opposite the anchor 13, and a locking member 18 is then preferably applied to the terminal 19 of the tape.

The locking member 18 is preferably in the form of a plate having a plurality of slots 20 and 21 of a size sufficient to pass portions of the tape through the respective slots. In applying the locking member to the terminal 19 of the tape, either of the slots may be employed, and the end of the plate adjacent the employed slot is preferably brought into engagement with the container immediately below the lower edge of the side wall flange 3 in such a manner that the locking member has a locking seat relative to the flange. The extremity 22 of the tape is then extended between the container and the anchor 12, as shown in Fig. 4, whereupon it is bent upwardly and extended through the slot in the locking member not employed for first extension of the tape terminal through the locking member.

After passage of the extremity 22 through the other slot in the locking member, it is bent outwardly, as shown in Fig. 5, and downwardly, as shown in Fig. 1, to positively lock the fastening device relative to the container and its closure.

In operation, the several bends of the tape each tend to maintain the tape in fastening relation to the container and closure, and by maintaining the tape in taut condition during the bending operations thereof, a positive fastening of the closure is secured. By bending the tape inwardly on the line 23, Fig. 5, for extension through the slot of the locking member, the locking member is forced inwardly into engagement with the container below the flange to enhance the locking action of the fastening device. The extremity 22 of the tape, when forcibly folded downwardly, as shown in Fig. 1, further tends to force the locking member inwardly and tensions the tape, with the result that the tape lies flat and thus minimizes open projecting edges of the tape and locking member to thus create a safety factor in preventing cutting or scratching of handlers of containers equipped with fastening devices in accordance with the present invention.

In Figs. 6 to 8 inclusive, a modified form of locking member 24 is illustrated in association with a container 25 comprising a side wall provided with an outwardly and downwardly turned flange 26, and a closure 27 spaced above the side walls by upstanding end walls, not shown.

An anchor 28, similar to the anchors 12 and 13, previously described, is also provided on the container, and an elongated element 29, similar to the element 14 in the preferred form of invention, is also provided.

In this instance, the locking member 24 comprises a washer consisting of a plate having an aperture 30 of a size sufficient to pass a multiple thickness of the element 29 therethrough.

In applying the fastening device to a container and closure in accordance with the modified form of invention, the illustrated end of the elongated member 29 is passed through the aperture in the washer 24 and extended to the anchor 28. The elongated member is drawn tight and the edge of the washer pushed up into engagement with the bottom edge of the flange

26 for locking seating engagement therewith. The outer extremity 31 of the element 29 is then folded outwardly and upwardly, as shown in Fig. 7, over the outer face of the anchor 28, and is then again passed through the aperture 30 in the washer 24. The element 29 is maintained in tightly drawn condition and then turned downwardly on the fold 32, Fig. 8, into overlapping engagement with itself, as shown at 33, the overlapping engagement forcing the washer inwardly to minimize projecting edges thereof and tensioning the element 29 to positively lock the closure in container closing condition.

It is apparent, therefore, that a fastening device has been provided by the present invention which transversely braces a closure for a container and prevents buckling of the closure upwardly out of confining engagement with commodities packed in the container. The closure thus normally contacts the commodities in the container and prevents their relative movement, when packed, in such a manner that impacts are avoided among the commodities and their preservation through lack of bruising is thus enhanced.

It is further apparent that danger of injury through handling the containers is minimized through lack of projecting edges of the fastening device, and that a positive lock is provided by the invention which allows the container to be opened for inspection and like purposes, the fastening device being susceptible of reuse if desired.

What I claim and desire to secure by Letters Patent is:

1. In combination with a container and a closure therefor, an abutment on one side of the container, an anchor member fixed to the container below said abutment, a tape having one end engaging said closure and extending across said abutment to be looped around the anchor member and providing a retractively extending terminal, and a locking device comprising a plate member slidable on said tape and adapted to engage said abutment, said plate member being shaped to produce a bight in the tape when the plate member is moved from an angular position relatively to the tape into a substantially parallel position, said plate member having an opening to pass said terminal of the tape and to form a fulcrum for drawing the terminal of the tape over the plate member to effect a bight in said tape when the plate member is engaged with said abutment.

2. In combination with a container and a closure therefor, an abutment on one side of the container, an anchor member fixed to the container below said abutment, a tape having one end fixed to the side of the container opposite said anchor member and extending over the closure and across said abutment to be looped around the anchor member and providing a retractively extending terminal, and a locking device comprising a plate member slidable on said tape and adapted to engage said abutment, said plate member being shaped to produce a bight in the tape when the plate member is moved from an angular position relatively to the tape into a substantially parallel position, said plate member having an opening to pass said terminal of the tape and to form a fulcrum for drawing the terminal of the tape over the plate member to effect a bight in said tape when the plate member is engaged with said abutment.

JAMES F. CLEARY.
